DISPENSING CIGARETTE CARTON

Harter E. Sweeney, Lafayette, Ind.

Application May 2, 1955, Serial No. 505,451

1 Claim. (Cl. 206—56)

This invention relates to a cigarette carton construction.

It is the primary object of this invention to provide a cigarette carton of such construction and arrangement that it may readily be converted by the purchaser into a gravity feed receptacle for mounting at a convenient place in a house or building.

It is a further object of the present invention to provide a carton of such character and construction that it is equally as useful as conventional cartons in connection with the storage, shipment, display and sale of cigarettes even though it has been formed to be readily converted into a gravity feed device.

It is a still further object of the present invention to provide a cigarette carton with means for preventing a predetermined number of packs therewithin from being gravity fed until desired. For example, means are provided to stop the two uppermost packs from descending in response to gravity so that when the user seems to be without additional packs he actually has two left. This will serve as a reminder that the carton is about empty. By removing the stop means the two packs may be gravity fed to the ejection point and, of course, used as desired.

It is a still further object of the present invention to provide means which serves not only to stop the descent within the carton of a predetermined number of packs, but as well as a reminder medium which may be put in the wallet or purse of the user to remind him or her to purchase an additional carton.

The full nature of the invention will be understood from the accompanying drawings and the following description and claims:

In the drawings:

Fig. 1 is a perspective view of one side of the carton which is in upright position with one pack of cigarettes shown partially removed.

Fig. 2 is a view similar to Fig. 1 except that the other side of the carton is shown.

In the drawings the cigarette carton shown generally at 10 is of that type and character customarily displayed and used during the Christmas holidays. This carton is provided with a loose closure flap 11 adjacent its top side 12, and it is preferable that it be glued to that side, i. e. exteriorly of the carton, by the distributor after the tax stamping procedure has been completed. The carton also comprises the ends 13, the bottom side 14, the back side 15 and the front side 16. Both ends 13 of the back side are free of the adjacent carton ends 13 to enable that side to be readily opened to expose the packs for tax stamping purposes.

In order to enable the purchaser to remove easily and quickly a portion of the carton that must be removed in order to carry out the purpose of the invention there are provided the perforations or score lines 17, 18 and 20 adjacent one end of the carton and in one side thereof. By punching or cutting out the portion

2

of the carton thus defined or bordered, the opening 21 is formed. The height of this opening will be substantially equal to but slightly greater than the width of a normal package of cigarettes such as 22 and 23 so that the packs may readily be ejected by normal finger pressure. The width of the opening is preferably the width of the carton side as shown and illustrated.

On the opposite or front side of the container are formed the perforations 24 herein shown to define an ellipse, although other shaped portions may be formed if desired. As will be observed by reference to Fig. 2, an opening 25 is formed in that side of the carton by punching or cutting out the portion or stop 26. This opening is long enough to expose a portion of each of the two adjacent packages of cigarettes and is large enough to permit ready entry of a finger or thumb of the user so that by pushing on one of the packs it may be forced out of the carton. At such time as it is forced out a sufficient distance, the user may then grasp the pack with his forefinger and thumb and remove it all of the way from the carton. At is apparent, the opening 25 is in alignment with opening 21.

The cutout or punch-out ellipse 26 is not discarded but is used as a stop to prevent (so long as desired) the two uppermost packs from being fed downwardly by gravity with the other packs. To this end a slot 27 is formed in the front or back side of the carton, it being sized to enable a sufficient part of the stop to be extended therethrough to engage the bottom of the two uppermost packs and retain them in position until the stop is manually removed. The slot 27 can either be preformed in the carton, or subsequently cut or punched out by the purchaser. In the latter event it is preferable either to have perforations formed in the side in order to designate the proper position for the slot, or to have some legend such as a line indicate the desired location.

In use, the distributor or other "middle man" will preferably glue the free flap to the adjacent exterior side of the carton after the tax stamping procedure has been completed. Thus the inside of the carton is free of any flaps or marginal obstructions that might impede the free sliding of the packs. When the purchaser of the carton arrives home he can form the opening 21 by punching out or otherwise satisfactorily removing that punch-out portion of the carton defined by the score lines 17, 18 and 20. He will also remove the elliptical portion and, after first forming the slot, will insert that portion through the slot so that it abuts the bottom of the two uppermost packs and prevents them from being gravity fed when the carton is in the upright position shown in Figs. 1 and 2.

In order to make it possible for the carton to be hung from nails or other supporting media driven into or secured to the wall of a room the openings 28 are formed at opposite ends of the carton. These openings each have slots 28a radiating outwardly therefrom in a vertical plane relative to the axis of the carton in order to pass, for example, the head of a nail.

The carton may now be mounted upon the nails and supported in an upright position at two points instead of one, thereby preventing it from swinging or pivoting arcuately. As the lowermost packs are removed through the finger ejection method heretofore described the upper packs will be fed by gravity to the bottom 13a. When the carton appears to be empty there will actually be two packs left therewithin. At this time the user should remove stop 26 whereupon those packs will fall by gravity to the bottom of the carton from which they may be ejected when desired. The stop is preferably placed in a wallet or purse so that it may serve as a reminder that the smoker is down to his last two packs.

It is, of course, apparent that the various openings may

be formed on opposite sides to those shown and illustrated, if desired.

While the invention has been illustrated and described in detail in the drawings and foregoing description, the same is of be considered as illustrative and no restrictive in character, it being understood that only the preferred embodiment has been shown and described and that all changes and modifications that come within the spirit of the invention and the scope of the claim are also desired to be protected.

The invention claimed is:

A cigarette carton having two adjacent series of packages of cigarettes disposed therewithin comprising an enclosed container provided with top, bottom, front and back sides and with ends, a punch-out portion formed in one of said sides adjacent one of said ends, said portion being defined by perforations and removable to leave an opening for cigarette pack ejection, a second punch-out portion formed in the side opposite to that in which

15 said first portion is formed and in alignment with said first portion, said second portion being defined by perforations and removable to leave an opening for the reception of means to eject a package through said first opening, and a 5 third punch-out portion defining a slot in a side of said carton at a predetermined location in relation to two adjacent packages nearest an end of said carton, said last mentioned portion being defined by perforations, said second portion being sized to be inserted partially through 10 said slot for abutment with the bottom of said two adjacent packages of cigarettes.
